UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS.

COIN-DELIVERY MACHINE.

1,068,308.

Specification of Letters Patent. Patented July 22, 1913.

Application filed June 10, 1912. Serial No. 702,861.

To all whom it may concern:

Be it known that I, EDWARD J. BRANDT, a citizen of the United States, and resident of Watertown, in the county of Jefferson and State of Wisconsin, have invented certain new and useful Improvements in Coin-Delivery Machines; and I do hereby declare that the following is a full, clear, and exact description thereof.

10 The invention relates to an improvement in coin delivery machines, and more particularly to that type of machine now known as "Brandt automatic cashier". The machines of this type employ a series of operating keys, spring actuated rockers operated by the keys, and pushers operated directly through the rockers, the coins being ejected from a tray positioned at the front of the machine. The present invention is 15 designed more particularly to simplify the structures and to reduce the mechanism to a minimum number of parts, while maintaining the efficiency of the machine.

A further object of the invention is to 20 provide a machine of the character designated wherein coins in the tray may be secured against abstraction and the machine locked against operation, at the will of the operator.

25 30 A still further object of the invention is to associate with the delivery part of the machine a suitable device which enables the machine to be used conveniently with a change receiving receptacle such as a carrier for cash carrying systems.

Other objects of the invention will be apparent from the described structure, and will be hereinafter pointed out.

Figure 1 of the drawings represents a vertical section view of my improved machine having parts thereof broken away, the section being generally indicated by line 1--1 in the next figure of the series and parts being shown in actuated position; Fig. 2, a

40 45 horizontal section view of the machine generally indicated by line 2--2 in Fig. 1, and in this view some of the parts are broken; Fig. 3, a front elevation of the machine partly broken away; Fig. 4, a plan view of 50 the top of the machine; Fig. 5, a side elevation of a detachable coin-tray closure of the machine, partly broken away, and which of itself serves as a coin-tray when detached;

55 Fig. 6, a side elevation of a push-plate constituting a key-element of the machine; Fig.

7, a similar view of a push-button having a vertically slotted flat shank engageable with a similar shank of said plate; Fig. 8, a like view of a detail of the machine; Fig. 9, a partly section rear elevation of the same, 60 and Fig. 10, a plan view of a detachable element of the machine designed as a holder for a cartridge-type transportation device of a cash-carrier system.

One characteristic feature of the herein 65 described machine resides in the arrangement and construction of parts whereby but thirteen actuating keys can conveniently be employed for actuating the mechanisms employed to eject therefrom fractional coin in 70 varying sums from one cent to one dollar of United States money, nine of the keys, in one rank, being operative to effect the payment of a difference between one dollar and any amount less than that integer, while the 75 remaining four keys, in another rank, are operative to effect the payment in change of a total of five, twenty-five, fifty or one hundred cents respectively.

The improved machine contemplates the 80 employment of freely swinging hangers for supporting the pushers and associated therewith are operating levers which serve not only as levers for operating the pushers to eject the coins but also as a means for positively returning the pushers to their normal positions, the term "freely swinging" having reference to a construction wherein the hangers operate freely in their swinging movement independent of directly connected springs or weights.

85 90 The improved machine also includes a "universal rocker" in the path of pivotal spring-controlled edgewise angle plates constituting bell-crank levers by which to operate coin-pusher hangers, and said rocker is intended to serve as part of an alarm mechanism by which to signal paying operations of said machine.

95 100 Another feature of the machine herein specified is a detachable coin-tray closure, that in normal position on said machine is a stop against the ejection of coin therefrom, and when detached, it has the function of a coin storage tray, the novel features above noted and others embodied in the aforesaid machine being hereinafter 105 specified in detail.

110 The machine embodies a casing of any preferred design, construction and number

of parts suitably assembled, and referring by numerals to the drawings, 11 in each instance indicates one of a group of vertically reciprocative edgewise plates such as are usual in "Brandt automatic cashiers". 5 Each plate 11 is provided with a spring-controlled shank 11' guided in a slotted top-plate 12 of the machine-casing, and in another slotted plate 18 within said casing. 10 Each of the plate-shanks is in engagement with the slotted shank 14' of a push-button 14, and the push-button shank is also guided in the plate 12 aforesaid. Each plate 11 and the push-button 14 therewith constitutes what is hereinafter termed a "key" of 15 the machine, its general construction being that originally disclosed in Patent No. 824,841, July 3, 1906. As is also usual in "Brandt automatic cashiers", the plate portion 11 of each key is provided with a foot or feet 11", and in the present machine each foot is opposed by one of a series of edgewise angle-plates constituting bell-crank levers 15 all fulcrumed on a single 20 rod 16 having preferably bushed ends engaging supports 16' in the machine-casing, in which they are held by overlying screws 16" or other suitable means, it being understood that the levers are actuated singly and 25 associated by the keys of the machine. A spiral-spring 17 connects the rear arm of each lever 15 with a serially recessed angle-plate 18 secured at each end to an inner upper ledge 19 of the machine-casing, each 30 ledge being vertically recessed to form a seat in which a preferably bushed end of a rod 20 is held by an overlying screw 20' or other suitable means. 35

The rod 20 serves as a support for as 40 many pendant swing-hangers 21 as there are bell-crank levers 15 in the machine. Each hanger is free to swing and is guided in a recess of the plate 18 and is straddled by a forked end of a coin-pusher 22 pivoted 45 thereto. As a matter of detail, the pivot-pin 23 for each coin-pusher has a flange-head, and one end of a leaf-spring 24, fastened by a screw 26 to the adjacent hanger, engages the pin-head against its flange, as 50 is best shown in Fig. 9, similar means for preventing automatic separation of a coin-pusher from its carrier having been originally disclosed in the application aforesaid.

A spiral-spring 27 connects a fork-branch 55 of each coin-pusher with the widened lower end of the hanger 21 to which said pusher is pivoted, and an anti-friction roller 28 carried with said hanger opposes the forward arm of one of the levers 15. This 60 lever-arm is guided between the hanger and a guard 29 parallel to the same, the guard being fast on a spacing-rivet 30, as is also best shown in Fig. 9, and the spindle 28' for said anti-friction roller 28 is fast in said 65 hanger and guard.

From the foregoing it will be readily understood that each of the coin-pusher hangers is swung forward as a result of a rock of a lever 15 from normal position, and to deaden sound of impact of said hangers 70 against the back of a front-plate 32' of the machine-casing below a rearwardly inclined coin-tray 31, an interposed buffer-strip 32 of wood or other suitable material is employed. On return of the lever 15 to normal position, its forward arm operates upon the spacing-rivet 30 in its path to thereby retract the companion hanger and coin-pusher therewith, the operation being automatic, as 75 a result of contraction of a previously expanded spring 17 when the actuating-key for said lever is relieved of pressure. It will thus be seen that the levers 15 serve as a means for moving the hangers forward and as positive means for retracting the 80 same. Under ordinary conditions, the hangers would, by gravity, move backward as soon as the pressure on the levers 15 has been released, but owing to the presence of coin in the tray and possible frictional contact with the guides, interfering with such normal backward movement, it has been found expedient and advantageous to positively retract the hangers in the manner 85 above stated. As a guide for the lower ends 90 of the aforesaid hangers, a serially recessed angle-plate 18' is fastened to a bottom-plate 33 of the machine-casing. 95

The top-plate 12 of the machine is inset at such an elevation as to provide for sufficient length of key-stems without undue projection of the same above the aforesaid casing, and the push-buttons of the keys in the front rank are preferably inclined on 100 their shanks toward the operator so that 105 their indices may be more readily seen, the angle of inclination being such that is best adapted to facilitate rapid action of said keys.

The universal rocker 34 of the machine 110 opposes the rear arms of all the levers 15 and has preferably bushed crank-ends in supports 34' with which the machine-casing is provided, said rocker being connected by spiral-springs 35 with a serially recessed 115 plate 36 in which the rear arms of said levers are guided, said plate being secured at its ends to supports 36' with which said casing is provided. The springs 35 expand when the rocker 34 is depressed and primarily assist to contract to automatically return said rocker to normal position when relieved of pressure. The spring actuated rocker serves also to modify the actuation of the bell crank 15 in resisting their movement under key pressure, thus slowing up on the ejecting action or impulse of the ejector mechanism, after the primary activating impulse has been applied. Another 120 guide-plate 36" is provided for said levers. 130

Shown in rigid connection with the rocker 34 is the shank 37' of a striker 37 for a gong-bell 38 having a post 38' clamped on the bottom-plate 33 by a set-screw 39 engaging a slot 40 in said plate so that said bell may be adjusted and held in or out of the path of its striker. The bell in the path of its striker constitutes an alarm mechanism by which to signal paying operations of the machine, but other alarm-mechanism or apparatus for the same purpose may be substituted without departure from what is herein claimed, and said alarm mechanism or apparatus may serve to call attention to the use of the machine by an uninterested person.

The coin-tray 31 is generally similar to the one shown in the application aforesaid and constitutes an inclined stationery front portion of the casing of said machine. The bottom of the coin-tray is provided with the customary guide-grooves for the coin-pushers aforesaid, and in Fig. 2, said pushers, as well as the corresponding coin-compartments of said tray are indexed 1, 2, 2, 5, 10, 10, 25 and 50. Immediately above the tray bottom, space is provided for the ejection of coin from each of the aforesaid compartments into an underlying chute 41 similar to the one in the application above noted, there being three compartments for cents, one for five cent coins, two for dimes and one each for quarters and halves of a dollar.

The organization of the machine is such that provision is had for the ejection of two coins at a time from each of the cents compartments 2, 2 of the tray 31 when the relative pusher is actuated and there is no obstruction in the path of said coin, but as concerns the remainder of said compartments, it is designed that but one coin at a time shall be ejected from each of the same.

Detachably secured to the front of the machine-casing, by screws or other suitable means, in register with the bottom opening of the chute 41, and in the path of a spring-controlled sliding trap-door 42 for said chute, is a holder 43 for a cartridge-type transportation device 44 of a cash-carrier system. The holder 43 is provided conveniently with an upstanding part 43^a in the form a ring as shown in Fig. 1, and this part 43^a constitutes in effect, when in position, an extension of the mouth of the chute 41. The holder 43 with the extension above referred to serves as means for maintaining the door 42 in its retracted position as shown in Fig. 1 and in that position the coins will be discharged directly into the device 44. The attachment 43 is also useful when the change-maker is employed for the purpose of depositing coin or change directly into pay envelopes, the part 43^a constituting in that particular an extended mouth for the chute.

The form of the holder may be varied from that shown in Figs. 1 and 10, to accommodate the transportation devices of varying types of cash-carrier systems. The purpose of the trap-door 42 is the same as was originally disclosed in the application aforesaid, and it becomes effective when the holder 43 is detached from the machine.

In detachable connection with the machine is a closure 46 for the coin-tray 31, said closure being itself a counterpart of said tray and serving, when off said machine, as a storage-tray for coin transferred thereto. The front of the closure is preferably provided with sight-openings through which to view the compartments of the coin-tray 31 and their contents, and also with indices 1, 1, 1, 5, 10, 25, 50, for the coin in said compartments, said sight-openings and indices being best shown in Fig. 3.

To provide for support of the coin-tray closure in an inclined position off the machine, and as shown in Fig. 5, its front is provided with knobs 46 conveniently arranged. The top of the closure is preferably provided with a series of slots 47, through which to drop coin into the compartments of the tray 31 with which said slots register, and said top of the closure extends over spring controlled pins 48 slideable in sockets provided in the back of said tray. One of these pins 48 is shown in Fig. 4, and a stop-screw 49 therewith engages a play-slot 51 in the tray-back.

The coin-tray closure is provided with side lugs 52 that have sliding engagement with hook-lugs 53 of the machine-casing, and a fool-lug 54 of said closure is guided between the tray 31 and a lug 55 of said casing. Another fool-lug 56 of the coin-tray closure is notched to constitute a bolt engageable with as many spring-controlled tumblers as may be desirable in a chamber with which the machine-casing is provided, one such tumbler 57 being shown in Fig. 1. The engagement of the bolt with the tumbler is automatic, and said tumbler is retracted by means of a removable key 58 guided in a slot leading from the front of the machine into said chamber.

Two notches are shown in the bolt 56, and the upper notch being engaged by the tumbler 57, the closure 46 is held down in the path of the lowermost coins in the tray 31, to prevent ejection of the same, the pins 48 being retracted against spring-resistance. Upon disengagement of the tumbler from the upper notch of the bolt, there is automatic lift of the pins 48 to elevate the closure 46 and thus afford coin-clearance, the lower notch of said bolt being then caught by said tumbler to lock said closure against removal from the machine.

In order to hold the key 58 against accidental displacement from the slot in which

it is guided, a spring-controlled detent-ball 59 is arranged to have engagement with a depression in said key. The spring 60 and a confining screw 60' for the same over the ball 59, are in an aperture with which a lug 61 of the machine-casing is provided.

I claim:

1. In a coin delivery machine, the combination with a casing, having a series of 10 coin holders extending upwardly at the front thereof, a series of reciprocating key members extending through the top of the casing adjacent the upper end of the coin holder, a series of pendant free swinging hangers 15 pivotally supported at their upper ends near the upper part of the casing between the holder and the keys, pushers pivotally supported on the hangers and forwardly swinging bell cranks loosely engaging the lower 20 ends of the hangers and extending rearwardly below the ends of the keys, substantially as described.

2. A coin-delivery machine comprising a series of swing-hangers, coin-pushers in connection with the hangers, an antifriction roller and a stop carried by each hanger, a corresponding series of levers each of which engages between the anti-friction roller and stop of a hanger, and means for actuating 30 the levers singly and associated.

3. A coin-delivery machine comprising serially recessed stationary plates, a series of swing-hangers guided in the recesses of a pair of the plates, coin-pushers in connection with the hangers, a series of hanger-operating levers guided in the recesses of another pair of similar plates, and means for actuating the levers singly and associated.

4. A coin-delivery machine comprising 40 serially recessed stationary plates, a series of swing-hangers guided in the recesses of a pair of the plates, coin-pushers in pivotal spring-controlled connection with the hangers, a series of spring-controlled hanger operating levers guided in the recesses of others of said plates, and spring-controlled keys by which the levers are opposed singly and associated.

5. A coin-delivery machine comprising a 50 series of swing-hangers, spring-controlled coin-pushers a pivotal connection between the pushers and the hangers, and leaf-springs that being attached to said hangers engage said pins against flanges of the same.

6. In a coin delivery machine, the combination with a casing, and a series of operating keys, of a series of hangers pivotally supported at their upper ends adjacent the upper part of the casing, coin pushers associated with the hangers, and spring retracting levers for operating said hangers in opposite directions.

7. In a coin delivery machine, the combination with a casing, and a series of keys, of a series of hangers pivotally supported

at their upper ends in the casing, coin pushers pivoted on the hangers, springs connected to the pushers and hangers, and pivoted spring actuated levers in operative association with the keys and slidably engaging said hangers.

8. A coin-delivery machine having a chute into which coin are ejected, a spring-controlled sliding trap-door for the discharge opening of the chute, and a holder detachably secured to the machine in the path of said trap-door.

9. A coin delivery machine comprising a chute into which coin are ejected, a spring actuated trap door for the discharge opening of the chute, and a member detachably associated with the machine arranged in the path of the door for maintaining the same in an open position, substantially as described.

10. A coin-delivery machine comprising a compartment coin-tray having an open front, and a detachable closure for the said front and having coin inserting slots therein registrable with the tray-compartments over the same.

11. In a coin delivery machine a chute into which coin are ejected, said chute being provided with a discharge opening, of a trap door for the opening, and detachable means associated with the machine forming a continuation of the chute in line with the said opening and serving to maintain the door in an open condition.

12. A coin-delivery machine comprising a compartment coin-tray, a detachable counterpart closure for the same that of itself constitutes a similar tray off the machine, and supporting knobs projecting from the front of the closure.

13. In a coin delivery machine, the combination with delivery mechanism and a coin tray, of means for closing the tray and also for rendering inoperative the said mechanism.

14. In a coin delivery machine, the combination with coin ejecting mechanism, and a coin tray, of means associated with the tray and operated at the will of the operator for rendering inoperative the said ejector mechanism.

15. In a coin delivery machine, the combination with ejector mechanism, and a coin tray, of a closure for the tray, and means on the closure operated at will for preventing the ejection of the coin from the tray, substantially as described.

16. A coin-delivery machine comprising a compartment coin-tray, and a detachable closure for the same adjustable on the machine to constitute a stop against the ejection of coin from the tray.

17. A coin-delivery machine comprising a compartment coin-tray, and a detachable closure for the same adjustable on the ma-

chine to constitute a stop against the ejection of coin from the tray, and means for latching the closure in the path of said coins.

5 18. A coin-delivery machine comprising a compartment coin-tray, and a detachable closure for the same adjustable on the machine to constitute a stop against the ejection of coin from the tray, and means for 10 latching the closure in and out of the path of said coins.

15 19. A coin-delivery machine comprising a compartment coin-tray, spring-controlled sliding-pins guided in the back of the tray, and a detachable vertically slid able tray-closure having an upper rear flange that opposes said pins, and means for latching the closure against spring-resistance to constitute a stop against ejection of coin from 20 the tray.

25 20. A coin-delivery machine comprising a compartment coin-tray, spring-controlled sliding-pins guided in the back of the tray, and a detachable vertically slid able tray-closure having an upper rear flange that opposes said pins, and means for latching the closure against spring-resistance to constitute a stop against ejection of coin from the tray and also in position to clear 30 said coin.

35 21. A coin-delivery machine comprising a compartment coin-tray, a detachable spring-controlled closure for the tray provided with a bolt-lug, and a spring-and-key controlled tumbler in the machine engageable with said lug to hold the closure adjusted against spring-resistance.

40 22. A coin-delivery machine comprising a compartment coin-tray, a detachable spring-controlled closure for the tray provided with a two-notch bolt-lug, and a spring-and-key controlled tumbler in the machine engageable with one of the bolt-lug notches to hold the closure adjusted 45 against spring-resistance and with the other of said notches to hold said closure against detachment from said machine.

45 23. A coin-delivery machine comprising a compartment coin-tray provided with forward hook-lugs, a detachable closure for the tray having side lugs engageable with said hook-lugs and bottom lugs guided in the machine, one of the bottom lugs being a bolt, and a spring-and-key controlled 55 bolt-engaging tumbler in the machine.

24. A coin-delivery machine comprising a compartment coin-tray, a detachable clo-

sure for the same having a bolt lug, a spring-controlled tumbler in the machine engageable with said lug, a key for retraction of the tumbler, and a spring-controlled detent in said machine engageable with a depression provided in the key. 60

25. In a coin delivery machine, the combination with a casing, a series of pendant hangers having their upper ends pivotally mounted near the upper end of the casing, coin pushers pivotally supported adjacent the lower ends of the hangers, bell cranks engaging the lower ends of the hangers 70 below the pushers, reciprocating key members for operating the bell cranks, and a spring supported bar located below the rear free ends of the bell cranks and engaging the same, substantially as described. 75

26. In a coin delivery machine, the combination with a coin tray, a pusher mechanism associated therewith, a spring pressed movable closure for the tray, and a lock for retaining the closure in position against 80 the action of the spring.

27. In a coin delivery machine, the combination with a coin tray and pusher mechanism, of a closure for the tray comprising a sliding member, a spring normally tending to elevate the member, and a lock for retaining the member in a lowered position against the action of the spring, substantially as described. 85

28. In a coin delivery machine, the combination with a coin tray, and a series of actuating keys, a series of swinging hangers, pushers pivotally supported on the hangers, and extending in opposite directions therefrom, springs connecting the 90 hangers with the rear projecting ends of the pushers, and means for operating the hangers to reciprocate the pushers.

29. In a coin delivery machine the combination with a coin tray, and a series of 100 keys, of a series of spring actuated operating levers associated with the keys, a series of pendant free swinging members loosely associated with the levers, and operated thereby, and pushers pivotally supported on the said swinging members. 105

In testimony that I claim the foregoing I have hereunto set my hand, at Watertown, in the county of Jefferson and State of Wisconsin, in the presence of two witnesses. 110
EDWARD J. BRANDT.
